REED CUSHION LOCK

Arthur H. Noble, Pawtucket, R. I., assignor to
Rhode Island Warp Stop Equipment Company,
a corporation of Rhode Island

Application August 12, 1937, Serial No. 158,721

11 Claims. (Cl. 139—188)

This invention relates to a cushioning device for use in connection with a loom reed, and is more particularly an improvement of the device shown in the co-pending patent application of 5 Edwin C. Smith, Serial No. 110,834, filed November 14, 1936; and has generally the same objects in view as are set forth in said application.

An additional object of this invention is to lock the reed cushion so as to hold the reed positively against swinging movement during the 10 flight of the shuttle across the loom.

Another object of the invention is to provide a construction which while positively locking the reed and holding it against any resilient 15 movement at the time the shuttle is in flight, will release the reed so that it may be yieldingly cushioned at the time of beat-up of the filling which has been just previously positioned in the shed.

20 Another object of the invention is the provision of a simple lock for the reed cushion such for instance as a latch carried by the reed cushion mechanism and engageable with some fixed part of the loom as the lay moves forward toward 25 front center position.

Another object of the invention is the provision of a latch with parts so arranged as to engage a part carried by the breast beam and effectively release the locked cushioning mechanism just prior to the beat-up of the filling 30 which has been just previously positioned in the shed.

With these and other objects in view, the invention consists of certain novel features of construction, as will be more fully described, and particularly pointed out in the appended claims.

In the accompanying drawings:

Fig. 1 is a diagrammatic view illustrating the relation of the lay and reed with my cushioning 40 means and lock therefor shown in position on the lay and breast beam;

Fig. 2 is a perspective view of the reed mounting arm;

Fig. 3 is a front elevation of the part of the 45 sword and a part of the lay and reed showing the cushioning device and lock in assembled position;

Fig. 4 is a perspective view of the member providing the pivot stud for the reed mounting arm;

50 Fig. 5 is a sectional view through the lay and showing the cushioning device mounted thereon with its lock;

Fig. 6 is a view similar to Fig. 5 but showing the lock as moved to released position;

55 Fig. 7 is a perspective view of the cushioning

device and lock separate from its mounting on the lay;

Fig. 8 is a perspective view of one of the latch members of the lock detached from the remainder of the mechanism.

In weaving fine goods and particularly rayon and kindred synthetic fibers, it is essential that the reed action in applying pressure and in releasing that pressure be gradual and free from irregularities due to uncontrolled friction or obstruction due to uneven wear of co-acting surfaces or mis-application of the forces invoked in actuating and controlling the reed. It is desirable that the reed "encounter the pick" and move it at all times to ultimate position with a steady 10 and relatively gentle elastic pressure and then accomplish the ultimate placement and incorporation of the pick with the fabric by means of more intense but equally firm steady elastic pressure. This desired action is accomplished by the 15 use of some yielding means such as a spring or a plurality of springs arranged to increase its or their intensity throughout the restricted range of movement of the reed in beating up the pick.

20 This spring pressure which serves to hold the reed in place is undesirable, however, during the flight of the shuttle as the reed serves as a guide for the travel of the shuttle, and accordingly, it is desired that the reed be held positively with 25 reference to the lay with no opportunity for resilient movement while the shuttle travels across the lay; and in order to accomplish this result I have provided a lock which will positively prevent any movement of the reed with 30 reference to the lay and thus prevent the reed from moving at the time of the flight of the shuttle across the lay; and the following is a 35 more detailed description of the present embodiment of this invention, illustrating the preferred means by which these advantageous results may be accomplished:

With reference to the drawings, 10 designates the breast beam over which the finished fabric 11 is drawn. 12 designates generally the lay mounted upon swords 13 to be swung about a 45 rock shaft (not shown) by the crank arm 14 from the crank shaft 15 to move the lay with the reed holder 16 and reed 17 to beat-up the pick previously placed in the shed 18 formed by the harnesses 19 and 20 which raise and lower the warps 21 and 22 drawn from the warp beam 23 over the guide 24 and through the lease 25, the foregoing being all usual loom structure and old in the art. The lay 12 is mounted upon a bracket 26 on the lay sword 13, and this bracket extends 50

55

upwardly as at 27 as a continuation of the upper end of the sword and has mounted thereon the L-shaped pivot block 28 adjustable in the slot 29 and which is provided with a cone projection 30 to enter the opening 31 in the arm 32 which constitutes one of the bearings by which the reed is pivotally or pendulously mounted on the lay, this arm having an upper reed holder 33 and a lower reed holder 34 to receive the reed 16 therein. The upper reed holder is secured to the arm 32 by the bolt 30 extending through slot 81 and held in position by the wing nut 82, while the lower reed holder is suitably secured in the L-shaped lower end 83 of this arm, as shown in Fig. 2, such as by fastenings extending through the openings 84. Thus, by this mounting the reed holder with the reed therein is capable of swinging about the pivot 30 as a center as pressure is brought to bear upon the front side 20 of the reed such for instance as during the beat-up of the pick.

In order to control rearward swinging of the reed I have provided a bracket which is designated generally 35 and is shown in perspective in Fig. 7, which provides a face 36 to engage beneath the lay 12 with a flange 37 to engage the front of the lay as also shown in Fig. 5, while lugs 38 with openings 39 provide a convenient means for fastening this bracket to the lay in the position shown. This bracket provides a short downwardly extending arm 40 at the front of the bracket and a longer downwardly extending arm 41 at its other end, this latter arm 41 being provided with a projecting tongue 42 to which the bifurcated end 43 of a lever 44 is pivoted by means of a pin 45, this lever being provided at its upper end with an anti-friction roll 46 which bears against a plate 47 upon the reed holder for controlling the movement of the reed holder and the reed therein. This lever 44 is controlled by means of a rod 48 which extends through a slot 49 in the lever and is provided with a nut 50 and washer 51 providing a suitable abutment through which the lever is pulled toward the reed. This rod 48 extends through the arm 41 and also through an opening 52 in the arm 40, which opening slidably receives a sleeve 53 having a flange 54 to engage the surface of the arm 40 about the opening and limit its movement therethrough. A recess 55 may be provided in the arm of the depth substantially the thickness of the flange to receive this flange, as illustrated in Fig. 5. The flanged end of the sleeve 53 is partially closed as at 56 with an opening 57 therein for free sliding therethrough of the rod 48. This rod 48 is threaded at its free end 58 to receive the nut 59 and abutment washer 60. This washer serves as an abutment for one end of the compression spring 61 while the other end extends freely into the sleeve 53 and engages the closed end 56 of the sleeve so as to exert pressure tending to move the abutment 60 to the right, as shown in Fig. 5.

A sleeve 62 through which rod 48 extends is threaded through the opening 63 in the arm 41 by which it may be readily adjusted by its head 64 and is held in adjusted position through this arm by means of the lock nut 65. This sleeve 62 provides an abutment for a spring 66 which is heavier and stronger than the spring 61 and which acts between the end 67 of the sleeve 62 and the closed end 56 or flange 54 of the sleeve 53 tending to force the sleeve 53 to the right, as shown in Fig. 5, and serving to control any slid-

ing movement of the sleeve 53 through its opening 52.

In order to positively lock the rod 48 against any movement and also lock the lever 44 firmly against the reed holder and hold the reed against any movement relative to the lay, I have provided a locking means consisting of a pair of latches 70 pivoted as at 71 on the bracket 35 each pulled by means of spring 72 to swing the same about its pivot and move the portion 73 thereof back of the abutment washer 60 so as to positively prevent sliding movement of the rod 48 rearwardly. Each of these latches has an ear 74 extending upwardly to engage a trip finger 75 mounted on the breast beam 10 and extending downwardly into the path of movement of the latches 74 so that as the lay moves forward the ear 74 will engage this finger 75 and swing the latch about its pivot 71, as shown in Fig. 6, to remove the same from engagement with the abutment washer 60.

In operation, as the lay swings forward by reason of the crank arm 14 the ears 74 will engage the fingers 75 and lift the locking latches from locking position. The reed will then engage the fell of the cloth designated 76 and as beat-up occurs the reed holder will swing backwardly, moving the lever arm 44 which in turn draws the rod 48 to first compress the light spring 61 until the washer 60 engages the end 77 of the sleeve 53, whereupon further movement of the lever and rod will cause the sleeve 53 to slide through the arm 40 to compress the spring 66, and this being of a greater strength will apply greater pressure upon the reed holder and reed until the limit of beat-up has occurred, whereby successive action of the springs causes a multiplied pressure to be provided, the next succeeding spring coming into action only after the resistance of the previous spring is exhausted. Then as recession takes place a strong spring 40 will first move outwardly followed by the movement of the parts by the weaker spring and as the lay recedes from the breast beam the latches 70 will drop back of the abutment of the washer 60 that the parts again assume the position shown in Fig. 5, in which position the reed is positively locked against movement and will remain so locked during the remainder of the cycle of the crank shaft and during the flight of the shuttle and until the next cycle of the crank shaft brings the lay forward again to beat-up position when the same process will be repeated.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a fly shuttle loom, a reciprocating lay, a shuttle, a reed mounted on the lay for rearward movement relative thereto at the time of beat-up, means yieldingly opposing said rearward movement of the reed at the time of beat-up, and means to engage said yielding means and through it positively lock the reed against movement relative to the lay during the flight of the shuttle but to release the reed at the time of beat-up.

2. In a fly shuttle loom, a reciprocating lay, a shuttle, a reed mounted on the lay for rearward movement relative thereto at the time of beat-up, means yieldingly opposing said rearward movement of the reed at the time of beat-

60

70

75

up, and means to engage said yielding means and through it positively lock the reed against movement relative to the lay at all times except at the time of beat-up.

5 3. In a fly shuttle loom, a reciprocating lay, a shuttle, a reed mounted on the lay for rearward movement relative thereto at the time of beat-up, means yieldingly opposing said rearward movement of the reed at the time of beat-up, and means wholly carried by the lay to engage said yielding means and through it positively lock the reed against movement relative to the lay at all times except at the time of beat-up.

10 4. In a fly shuttle loom, a reciprocating lay, a shuttle, a reed mounted on the lay for rearward movement relative thereto at the time of beat-up, means yieldingly opposing said rearward movement of the reed at the time of beat-up, and means carried by the lay throughout its path of travel to engage said yielding means and through it positively lock the reed against movement relative to the lay, said means being released at the time of beat-up by engagement with some part with reference to which the lay moves.

15 5. In a fly shuttle loom, a reciprocating lay, a shuttle, a reed mounted on the lay for rearward movement relative thereto at the time of beat-up, means yieldingly opposing said rearward movement of the reed at the time of beat-up, and a latch to engage said yielding means and positively lock the reed against movement relative to the lay at the time of shuttle flight.

20 6. In a fly shuttle loom, a reciprocating lay, a shuttle, a reed mounted on the lay for rearward movement relative thereto at the time of beat-up, means yieldingly opposing said rearward movement of the reed at the time of beat-up, and a latch carried by the lay to engage said yielding means and positively lock the reed against movement relative to the lay at the time of shuttle flight.

25 7. In a fly shuttle loom, a breast beam, a reciprocating lay, a shuttle, a reed mounted on the lay for rearward movement relative thereto at the time of beat-up, means yieldingly opposing said rearward movement of the reed at the time of beat-up.

time of beat-up, and means carried by the lay throughout its path of travel and acting through said yielding means to positively lock the reed against movement relative to the lay, said means being engageable with a part carried by the breast beam to move the latch to release the reed at the time of beat-up.

5 8. In a fly shuttle loom, a reciprocating lay, a shuttle, a reed mounted on the lay for rearward movement relative thereto at the time of beat-up, and a latch carried by the lay throughout its path of travel to positively lock the reed against movement relative to the lay, said latch being engageable with a fixed part with reference to which the lay moves to move it to released position at the time of beat-up.

10 9. In a fly shuttle loom, a breast beam, a reciprocating lay, a shuttle, a reed mounted on the lay for rearward movement relative thereto at the time of beat-up, means yieldingly opposing said rearward movement of the reed at the time of beat-up, and a latch carried by the lay throughout its path of travel to positively lock the reed against movement relative to the lay, said latch being engageable with a part carried by the breast beam to move the latch to release the reed at the time of beat-up.

15 10. In a fly shuttle loom, a reciprocating lay, a shuttle, a reed mounted on the lay for rearward movement relative thereto at the time of beat-up, and means carried by the lay throughout its path of travel to positively lock the reed against movement relative to the lay, and a finger carried by a fixed portion of the loom to engage said means as it moves to beat-up position to move the means to released position.

20 11. In a fly shuttle loom, a reciprocating lay, a shuttle, a reed mounted on the lay for rearward movement relative thereto at the time of beat-up, and a latch carried by the lay throughout its path of travel to positively lock the reed against movement relative to the lay, and a finger carried by the breast beam to extend into the path of travel of said latch to engage the latch and move the same to release position at the time of beat-up.

25 ARTHUR H. NOBLE.
